CHARLES F. LEFEVER AND DANIEL M. LEFEVER, OF SYRACUSE,
YORK.

SINGLE-TRIGGER MECHANISM FOR DOUBLE-BARREL GUNS

No. 810,871.

Specification of Letters Patent.

Patented Jan. 21,

Application filed February 14, 1903. Serial No. 143,287.

To all whom it may concern:

Be it known that we, CHARLES F. LEFEVER and DANIEL M. LEFEVER, of Syracuse, in the county of Onondaga, in the State of New York, have invented new and useful Improvements in Single-Trigger Mechanism for Double-Barrel Guns, of which the following, taken in connection with the accompanying drawings, is a full, clear, and exact description.

This invention relates to improvements in single-trigger mechanism for double-barrel breech-loading guns.

The primary object of these improvements is to prevent the accidental or premature firing of either of the barrels of the gun by the recoil or rebound incidental to the discharge of the other barrel and to enable the operator to control the operation of the hammers as positively and safely as though each hammer were controlled by a separate trigger.

Another object is to provide means under the control of the operator whereby the same (either right or left hand) barrel may be fired first after each successive breaking and closing of the gun.

Referring to the drawings, Figure 1 is a top plan of my improved trigger mechanism, showing the parts in their normal position assumed when the gun is closed and both hammers ready to be fired. Fig. 2 is a sectional view taken on line 2-2, Fig. 1. Fig. 3 is a sectional view similar to Fig. 2, the hammer, trigger, and sear-operating pawl being shown in the fired position. Fig. 4 is a side elevation of the parts seen in Fig. 1, the right-hand hammer and its sear being shown in the fired position, while the left-hand hammer is in the position to be fired, the position of the trigger being normal. Fig. 5 is an elevation similar to Fig. 4, showing the hammers, sears, trigger, and pawl in their fired positions. Fig. 6 is a sectional view similar to Fig. 2, except that the sear-operating pawl is shown in section and the mainsprings and sears are removed. Fig. 7 is a perspective view of a weighted sear-operating pawl. Fig. 8 is a perspective view of the sears and the shoulder which is movable into and out of operative engagement with the sears.

Similar reference characters indicate corresponding parts in all the views.

In carrying out the objects of the invention we provide a trigger-plate 1, upon which is mounted a trigger 2, hammers 3 and 4, sears 5, and a cock 6, all of which parts perform the functions and are adapted to coöperate the remaining features of our invention as hereinafter described.

The trigger 2 is pivoted at 7 between front and rear ends and is provided with a forwardly-extending arm 8, to which is secured one end of a light spring 9, the other end extending rearwardly beyond the trigger 2 for carrying a weighted sear-operating pawl 10. This trigger 2 is located substantially midway between the hammers 3 and 4, and is provided with a rearwardly-extending arm 11, which is adapted to engage a bearing 12 for limiting its upward movement rather than for limiting the rearward movement of the finger-piece of the trigger. Pawl 10 is pivotally mounted upon the rear end of the trigger 2 and is provided with teeth or shoulders 13 and 14 which are movable into and out of engagement with similar teeth or shoulders 15 and 16, respectively, formed upon the rear ends of the hammers 3 and 4, the rear end of each hammer being provided with a shoulder 17 for carrying a weighted sear 5, said pawl being weighted in such a manner that the recoil of the gun will, with its own inertia, cause it to snap into engagement with the shoulders 14 and 15—in other words, the pawl is automatically forced to its operative position when either of the barrels is discharged. The purpose of this weighted pawl is to prevent the accidental or premature discharge of one of the barrels at the time of the discharge of the other and also to prevent the simultaneous discharge of both barrels.

It is well known that when the gun is discharged the operator is voluntarily pulling the trigger and that the recoil rearwardly and forwardly are almost instantaneous. The recoil forwardly is the pull on the trigger, so that when the gun is discharged the finger-piece of the trigger 2 is caused to move forwardly and to disengage from the finger of the operator, which permits the trigger to instantly assume its normal position, and the rebound being instantaneous produces an involuntary forward movement of the trigger by the operator, which causes the firing of the other barrel. This is due to the fact that the pawl is instantaneously caused to move forwardly into its operative position at the instant of discharge, and the account of its inertia cannot possibly be overcome.

the position at the rebound in
ment with the sear when the
ll takes place. In order that
against the accidental dis-
in may be further carried out,
pawl with a second tooth or
hich automatically interlocks
oth or shoulder 17 of a spring-
shoulders being adapted to in-
ch other when the recoil takes
he rebound will not affect the
further explanation of this
t may be stated that the teeth
and 15 of the pawl and sears,
re so positioned relatively to
t when the involuntary pull
r takes place which would re-
der 16 from the detent-shoulder
14 is elevated above the
o that they cannot interlock
r until the pull upon the trig-
whereupon the tooth 14 drops
position for engaging and op-
r when the trigger is voluntar-
his is an important feature of
and it is apparent from the
on that the time between the
und of the gun upon the dis-
ort to permit the pawl 10 to
operative position in time to be
e involuntary pull upon the
he rebound.

, which is secured at one end
engages a shoulder 19 upon
side of its pivot and serves to
to its operative position when
holding engagement with the
7, this spring being very light,
s little resistance as possible

ly function of this spring be-
pawl to its position for en-
ilders 15 of the sears.

the sear of the fired hammer
ere with the operation of the
other hammer, we provide each
s with a cam-face or shoulder
upon the forward end of the
hammer is released and holds
the sear in its elevated inoper-
ut of the path of movement of
being operated to trip the
e mainsprings 4 operate their
mers and sears, one arm of
ng connected to a stirrup 21,
heel of the hammer, and the
es the sear at the rear of its
e point of the sear into hold-
t with a sear-notch 22 of the
ars being pivoted at 23 to the

ies desirable to fire the same
r each break and close of the
before provide means to opera-

tively connect the trigger with each of the 65
sears separately from the other sear, said
means consisting in this instance of a later-
ally-movable shoulder 24, which is adapted
to be moved manually between a shoulder 25
on the trigger and a similar shoulder 26 on
the sear, each sear being provided with one
of these shoulders 26, which project toward
each other from the heel of the sear. Any
desired means may be employed for moving
this shoulder 24 laterally into and out of reg-
istration with the shoulders 26; but we have
here shown said shoulder as mounted upon
the pin 12, which is movable endwise or lat-
erally in suitable bearings provided in the
trigger-plate, the opposite ends of said sliding
pin being visible when the parts of the gun
are assembled, so that the operator may read-
ily determine or ascertain the position of the
shoulder 24 with reference to the shoulders
26. The shoulder 24 forms the connection 80
between the trigger and the sear with which
said shoulder is registered, and said sear is
actuated by the shoulder 24 irrespective of
the pawl 10, which is normally in its inoper-
ative position when the hammers are cocked,
said pawl serving only to operate the sear
which is not in engagement with the shoul-
der 24.

In order to prevent the simultaneous dis-
charge of both barrels through the medium 95
of the pawl 10 and shoulder 24, it is neces-
sary to provide some means for forcing the
pawl to its inoperative position during each
break and close of the gun, and we therefore
provide the cocking-lever 6 with a rear-
wardly-projecting arm 27, which extends
through a slot 28 in the pawl and engages the
shoulder 19, also formed upon the pawl in
such position that when the cocking-lever is
rocked upwardly in the act of cocking the 105
hammers the arm 27 simultaneously rocks
the pawl to its inoperative position, as seen
in Figs. 2 and 6.

In the operation of our invention, assum-
ing that the hammers are in their cocked po-
sition, as seen in Fig. 2, at which time the
pawl 10 is thrown forward and the trigger is
normal and it is desired to fire the right-hand
hammer first, then the pin 12 is shifted later-
ally to throw the shoulder 24 between the 115
trigger and right-hand sear and out of aline-
ment with the left-hand sear. Now when
the trigger is pulled the right-hand sear is
tripped to release the right-hand hammer,
and during this operation the pawl 10 is ele-
vated by the trigger to disengage the shoul-
der 16 from the detent 17. When this ham-
mer is fired, the cam-face 20 operates upon
the forward end of the sear to elevate the
rear end of the sear to prevent engagement 125
therewith by the shoulder 14 when the trigger
is operated to trip the other sear, it being un-
derstood that when the trigger is held and

Locks, Single Trigger.

42

the spring 9 rocks the pawl 10 to its operative position the shoulder 14 is above the shoulder 15 of the left-hand sear and immediately upon the firing of the hammer, as described, the pawl 10 is returned to its inoperative position by the recoil and its own inertia and may be held in this position by the detent 17. Now if it is desired to fire the left-hand hammer it is necessary to draw the trigger back to disengage the shoulders 16 and 17 and then to release the trigger, so that the shoulder 14 may ride under the shoulder 15 of the left-hand sear, and when the trigger is again drawn back the left-hand sear is operated to release the left-hand hammer. Both hammers being now fired, it is desired to re-cock the same, which is done in the usual manner by breaking the gun to operate the cocking-lever 6, which simultaneously 20 turns the pawl 10 to its inoperative position ready for a repetition of the firing, as just described. If it is desired to fire the left-hand hammer first after each break and close of the gun, it is simply necessary to slide the pin 12 endwise to register the shoulder 24 with the shoulder 26 of the left-hand sear.

Having thus described our invention, what we claim, and desire to secure by Letters Patent, is—

30 1. In a single-trigger mechanism for double-barrel guns, the combination with the hammers, mainsprings and sears, of a trigger, a weighted pawl pivoted on the trigger to engage and trip the sear, a spring on the trigger operating to force the pawl into position to engage the sears, and a detent engaging and holding the pawl in its cocked position against the action of said spring, and means brought into action by the breaking of the gun to 40 force the pawl into position to be engaged by the detent.

2. In combination with the hammers, mainsprings and sears, of a double-barrel breech-loading gun, of a trigger, a movable element actuated by the trigger and means to force said element into position to engage and trip one of the sears when the trigger is pulled, said element being disengaged from the sear by its own inertia and the recoil of 50 the gun, a cocking-lever operatively connected to move said element to its inoperative position when the gun is "broken," and a detent to hold said element in its inoperative position while the gun is closed.

55 3. The combination with the hammers, mainsprings and sears of a breech-loading double-barrel gun, of a trigger, a weighted pawl actuated by the trigger to trip one of the sears, the inertia of the pawl and the recoil of the gun coacting to disengage the pawl and sear from each other when the gun is fired, and a detent for holding the pawl in its inoperative position.

4. The combination with the hammers,

mainsprings and sears of a breech-double-barrel gun, of a trigger, a pawl trigger to trip the sear when the trigger is pulled, said pawl being weighted to automatically from the sear-engaging spring to hold the pawl in said engagement, the inertia of the pawl and of the gun coacting to separate the faces of the pawl and sear when the gun is fired, and a spring-detent for holding the pawl in its inoperative position.

5. The combination with the hamsprings and sears of a breech-double-barrel gun, of a trigger, a movable manually to establish connection between the trigger and either sear separately from the other whereby either may be fired successively and separately the other barrel, a pawl actuated by means to move said pawl in position to engage and trip the sear for the barrel, and a cocking-lever connected to the pawl to its inoperative position to break of the gun.

6. The combination with the hamsprings and sears of a double breech-loading gun, of a trigger, an adjustable means to connect the trigger either sear separate from the other either barrel may be fired first and from the other after each break of and mechanism brought into action trigger whereby said other sear tripped to fire said other barrel, said mechanism including a sear-engaging pawl, for forcing it to its operative position detent for holding it in its inoperative position, the pawl being thrown to its inoperative position by its own inertia and the gun.

7. The combination with the hamsprings and sears of a double breech-loading gun, of a trigger, a pawl actuated by the trigger to trip the sears, said pawl being movable into and out of operation irrespective of the trigger, and a lever operatively connected to cock the hammers and to simultaneously move the sears in its inoperative position when the gun is broken.

8. In combination with the hamsprings and sears of a double-barrel gun, of a trigger, a trigger-plate, a pawl pivoted on the trigger and actuated to trip the spring on the trigger operating to force the pawl in position to trip the sears as the trigger is operated, the recoil of the gun causing the pawl operating to force it from said position against the action of the spring.

9. In combination with the hamsprings and sears of a double-barrel gun, of a trigger, a trigger-plate, a pawl pivoted on the trigger and actuated to trip the

g on the trigger operating to hold the
in position to trip the sears as the trig-
operated, the recoil of the gun and iner-
f the pawl operating to force the pawl
said position against the action of the
g, and a spring-detent on the trigger-
to engage and hold the pawl away from
ears.

In witness whereof we have hereunto set
our hands this 11th day of February, 1903. 10
